UNITED STATES PATENT OFFICE.

WILLIAM EMIL BOCK, OF EAGLE POINT COLONY, OHIO, ASSIGNOR TO BERTHA M. BOCK,
OF TOLEDO, OHIO.

CENTRIFUGAL MACHINE AND METHOD OF BALANCING SAME.

Application filed October 14, 1920. Serial No. 416,782.

To all whom it may concern:

Be it known that I, WILLIAM EMIL BOCK, a citizen of the United States, and a resident of Eagle Point Colony, in the county of 5 Wood and State of Ohio, have made an Invention Appertaining to Centrifugal Machines and Methods of Balancing Same; and I do hereby declare the following to be a full, clear, and exact description of the invention, such as will enable others skilled in 10 the art to which it appertains to make and use the same, reference being had to the accompanying drawings, and to the characters of reference marked thereon, which form a 15 part of this specification.

This invention relates to drying and separating machines of the centrifugal type, and more particularly to machines of this class adapted for the drying of clothes.

20 In the use of machines of this class considerable difficulty is experienced in maintaining a true rotary movement of the clothes container or bowl and eliminating gyrating movements and vibration thereof when running at high speed and the weight of the clothes or other matter being dried or acted on is not equally distributed therein.

The primary object of my invention is the provision in machines of the class described, 30 of means which is automatically operable by a running of the machine to equalize the weight in the container or basket thereof around its axis of rotation to cause a true running thereof at high speed and to prevent 35 the objectionable vibration which would otherwise be present.

Further objects and advantages of the invention will be apparent from the following detailed description thereof.

40 While the invention in its broader aspect is capable of embodiment in numerous forms, only a few embodiments thereof are illustrated in the accompanying drawings, in which,—

45 Fig. 1 is a central vertical section on the line 1—1 in Fig. 2 of a clothes drying machine embodying the invention, with the clothes container or basket tilted slightly to one side to admit the weight equalizing 50 liquid to one side of the container, and illustrating the action of such liquid when the container is rotated at high speed and the equalizing action is taking place. Fig. 2 is a horizontal section of the clothes container 55 on the line 2—2 in Fig. 3. Fig. 3 is a ver-

tical section of the container on the line 1—3 in Fig. 2. Fig. 4 is a central vertical section of a slightly modified form of the machine. Fig. 5 is a horizontal section on the line 5—5 in Fig. 4. Fig. 6 is a central vertical section of a different modification of the machine. Fig. 7 is a top fragmentary plan view of the container thereof, and Fig. 8 is a cross section of the control cam taken on the line 8—8 in Fig. 1.

Referring to the drawings, 1 designates a stationary base frame having an opening 2 in its top, 3 a cylindrical shell or casing rising from the frame around said opening and in communication at its top with the interior of a casing 4 which it supports. The casing 4 is of cylindrical form and has its bottom annularly dished around the upper end of the supporting shell 3 to form a water drainage trough 5 having a discharge outlet 6 at 75 one side. The casing 4 is provided in its top with a large opening 7 to render access to the interior thereof, which opening is closed by a cover 8 hinged, in the present instance, at one side of the opening.

80 A bracket arm 9 projects down from the frame 1 below the opening 2 and has a vertical bearing 10 in axial register with the opening and the casing 3. A shaft 11 is journaled at its lower end in the bearing 10 for rotary and axial movements therein and has universal rocking connection at its upper end with an open top cylindrical clothes container or bowl 12 disposed within the casing 4 and adapted to have rotary 90 movements therein with the shaft, as hereinafter described.

The container 12 is formed with an inner lining or shell 13, which is spaced from the bottom of the container 12 to form a false 95 bottom therefor, and has its side walls formed around the same with successive scallops 14, which meet at their edges with the outer wall of the container to provide the container wall with successive pockets or 100 spaces 15. These pockets or spaces extend at their tops to near the top of the container and at their lower ends to the bottom of the container, where they communicate with the space 16 between the bottom portions of the inner and outer walls of the container. The bottom space 16 is divided into a plurality of radial passageways by radial partitions 17 which extend from adjacent to the axis 105 of the container outwardly to the points 110

where the scallops 14 of the inner wall or lining connect with the outer wall so that each radial passageway communicates with a separate wall pocket 15.

5 The container bottom is provided at its center with a tapered socket member or cage 18, which is disposed between the central portions of the two bottom walls of the container and has its top open to the interior 10 of the container except for a removable cover 19 closing the same. The shaft 11 projects into the cage 18 and cooperates therewith to form a ball and socket joint for the container to permit it to assume different tilting 15 positions with respect to the shaft.

A closed-bottom cylindrical shell 21 encircles the shaft 11 between the bearing 10 and container 12, being fixed at its bottom to the shaft to rotate therewith. This shell 20 serves as a storage reservoir for the weight equalizing liquid 22 of the machine and has its top open and terminating adjacent to the bottom of the container 12. The upper edge of the shell 21 is provided with an annular channel 23 concentric to the shaft axis and receiving a combination ring gasket and valve 24 of rubber or other suitable yielding material of a resilient nature. This ring member is intended to fit up closely 25 against the bottom of the container 12 to normally maintain the same in level position, or with the axis of the container in true longitudinal alignment with the shaft axis, and at the same time is sufficiently compressible 30 in its nature to permit a rocking or tilting of the container in any direction with respect to the shaft when the container at one side of its axis is over-weighted with respect to the other side. The ring member 24 has 35 a pliant flange 25 projecting outward from its upper edge entirely therearound and fixedly secured at its outer edge portion to the bottom of the container in any suitable manner, as, for instance, by providing such 40 outer edge portion of the flange with a spring ring 26, which is firmly fitted against or in outwardly sprung engagement with a surrounding annular flange or shoulder 27 on the container bottom.

45 The outer casing of the container 12 is provided at its bottom with a circular series of openings 28 arranged concentric to the axis of the container and in position to be closed by the ring valve 24 when seated against the bottom of the container. These 50 openings are disposed without the inner ends of the radial pockets formed in the bottom space 16 of the container by the radial partitions 17 so that when the openings 55 28 are uncovered at one side of the container axis the equalizing liquid 22 is permitted, by centrifugal action, to pass through such openings and thence outward through the radial space 16 and up into the 60 registering pocket or pockets 15, thereby 65

effecting an automatic equalizing of the weight in the container. It will be understood that when the container is overweighted at one side by clothes or other matter placed therein, the gasket or valve 24 will be 70 compressed at such side by the tilting action of the container, and the container bottom at the opposite side thereof will be raised from the anchored body portion of the valve ring to uncover the openings 28 at such side, 75 as illustrated in Fig. 1. This figure also illustrates the form which the liquid takes within the container by reason of centrifugal force thereon when the container and shell 21 are rapidly rotated.

80 The shell 21 has an annular flange 29 depending from its bottom concentric to the bearings 10 and outturned at its foot to rest on a friction drive wheel 30 carried in the present instance by the shaft of a motor 31, 85 secured to the underside of the base frame 1. A control cam 32, carried by a shaft 33, is adapted to engage the foot of the flange 29 to effect a raising thereof from contact with the drive pulley 30, such raising being 90 permitted by reason of the shaft 11 being mounted for axial movements in the bearing 10. It is thus evident that a raising of the flange wheel 29 will effect a raising of the shaft and container and that the pulley 30, 95 when in driving coaction with said flange, will support the shaft and parts carried thereby so that no lower end thrust bearing for the shaft is required. The cam shaft 33 has a control arm 34 extending upward 100 therefrom at a side of the machine in convenient reach of the operator. The lower end of the bearing 10 is closed by a plug 35 to exclude dust and dirt therefrom.

105 The container 12 is provided in its periphery at points between the wall pockets 15 with vertical rows of wall perforations 36 through which the liquid extracted from the clothes or other matter within the container is permitted to pass by centrifugal action into 110 the outer receiving shell 4, such liquid being then drained from the bottom of the shell 4 through the drainage opening 6. The cage 18 has its interior in communication with the space 16 between the inner and outer walls of the container through openings 37, and the space within the cage is in communication with the interior of the liquid containing shell 21 through a passage 38 in the upper end of the shaft, thereby 115 providing an air passage between the interior of the shell 21 and the space 16 which facilitates the passage of liquid from one to the other of said container and space and prevents a vacuum from occurring in either. 120 In other words, as the liquid in the shell 21 passes into the equalizing space 16 and pockets 15 of the container, the air displaced by such liquid will pass from the pockets 125 and space 16 into the container, and vice 130

versa. A drainage of liquid from the container wall back into the shell 21, when a rotation of the container is stopped, is permitted through drainage openings 39 provided in the bottom wall of the container around the cage 18. The upper end of the shell 21 is braced with respect to the shaft 11 by a spider 40.

In the form of the invention illustrated in Fig. 4, the pockets in the container for the equalizing liquid are disposed within the container radially thereof so that the container is divided around its center into alternating pockets, one set of which are larger than the other and adapted to receive the clothes or other matter to be acted on while the other set receives the equalizing liquid.

In this form of the invention 41 designates the container or bowl, which is mounted for universal tilting movements on the upper end of the vertical drive shaft 42, the shaft bearing in the container bottom being enclosed by a cage 43, in the present instance, at its top. The container is provided interiorly between the cage 43 and its outer wall with a plurality of sets of radial partitions 44 with the partitions of each set forming narrow radially disposed pockets 45 therebetween in communication at their inner ends with the interior of the cage 43, and each also having an opening 46 in its bottom adjacent to its inner end. The spaces 47 formed by the partitions 44 are adapted to receive the clothes or other matter to be acted on and the peripheral wall of the container at the outer sides of the spaces 47 are perforated as shown at 48 to permit the radial discharge of liquid therefrom into the receiving space within the outer shell 4. The shell 49, which is carried by the shaft 42 and forms the liquid storage chamber, the same as in the form previously described, carries a ring gasket or valve 50 around its upper edge for seating against the bottom of the container 41 in closing relation to all of the openings 46 therein when the container is in normal level position. The ring valve 50 is compressible in nature, being, for instance, of rubber, and has a flange 51 projecting outward from its upper edge and clamped at its free edge portion to the bottom of the container by a clamping ring 52.

It is evident that with this form of the invention the openings 46 will be uncovered at one side of the container by the tilting of the container caused by a weighting down of the opposite side, and that when the container is rapidly rotated in such tilted position the liquid within the shell 49 passes upward and outward through the uncovered opening 46 and into the communicating liquid receiving pocket 45 of the container a sufficient extent to equalize the weight in the container around its axis and cause it to assume a level position. The liquid

which has been forced in this manner into a pocket 45 is permitted to drain therefrom, after a closing of the valve opening 46, by passing into the interior of the cage 43 and thence through a drainage passage 53 in the shaft back into the shell 49.

The form of the invention shown in Figs. 6 and 7 is similar to that shown in Figs. 4 and 5, except that a different form of valve is employed for controlling the discharge of weight equalizing liquid from the storage chamber into the equalizing pocket or pockets of the container. In this form of the invention 60 designates the base frame having the shell 61 rising therefrom and supporting at its top the casing 62 in which the container or bowl 63 is mounted. The shaft 64 carrying the container is journaled in a bearing 65 rising from the base frame 60 centrally within the shell 61 and carries a wheel 66 at its lower end below the frame 60 in position to rest on a friction drive wheel 67 of a motor 68. A plate or casting 69 is fixed to the bottom of the container 63 and is provided with a shaft receiving bearing part 70 in concentric relation to the container and provided in its lower end with a socket 71 for receiving a fixed flange or shoulder 72 on the shaft, such flange or shoulder being adapted to seat against the upper end of the socket and being keyed thereto by a pin 73, or in any other suitable manner to cause a rotation of the plate 69 with the shaft, and at the same time permit a rocking of one with respect to the other. Such rocking action of the plate and shaft is opposed by a cushion gasket 74, which is held within the outer end portion of the socket 71 and against the shaft shoulder 72 by a ring 75, which is threaded in the outer end of the socket. The interior of the container 63 is divided into a plurality of alternating and equidistantly spaced clothes containing pockets 76 and liquid receiving pockets 77 by partitions 78, the liquid pockets 77 opening at their inner ends into the interior of a centrally disposed cylindrical shell or cage 79. Each pocket 77 is provided in its bottom with an opening 80 in communication with a liquid storage chamber formed below the container around its supporting shaft by a shell 81, which is carried at its outer edge by the container bottom, the inner upper edge of the shell 81 projecting loosely up into an annular recess 82 in the bearing 70 to cooperate with liquid contained in the shell 81 to form a liquid seal at such point. Each opening 80 is normally closed by a valve 83, which has its stem projecting up into the respective pocket 77 and is normally retained seated by a spring 84. The upper end of the shaft 64 projects into the cage 79 and carries a spider 85 having an arm 86 projecting outward into each liquid receiving pocket 77 in posi-

tion to engage the upper end of the associated stem of a valve 83. It is therefore evident that any tilting of the container 63 with respect to the shaft, which is rendered possible by reason of the compressible nature of the gasket 74, will cause the spider arm 86 at the upwardly tilted side of the container to coact with the registering valve stem to effect a lowering of the valve to uncover the opening 80. When the container is rotated with such opening uncovered, the liquid in the chamber 81 will pass upward and outward by centrifugal action through the opening and into the outer portion of the associated pocket 77 to effect an equalizing of the weight in the container. The liquid in draining from the pocket 77 passes into the cage 79 and thence from the bottom thereof through openings 87 into the shell 81.

It is evident that my invention contemplates the provision in connection with a rotatable article or matter supporting member, of means which is automatically operable to act according to the speed of rotation of the member, and to the normal location of the center of inertia of the member relative to its axis of rotation, to counterbalance the member or shift the center of inertia thereof into register with the axis of rotation. It is also evident that in each of the forms of the invention illustrated any unevenness in the distribution of weight in the container or supporting member which causes an off-setting of the center of inertia of the member relative to its axis of rotation will be compensated for and the center of inertia and axis of rotation caused to register by reason of the weight equalizing mass, (in the present instance liquid), being released and passing by centrifugal action from the storage chamber therefor into the lighter side of the container, or at the opposite side of the axis of rotation thereof to its normal center of inertia. Shortly after starting the rotation of the container or supporting member, a sufficient quantity of liquid will have been admitted to the lighter side thereof to equalize the weight and prevent the vibration which would otherwise be present in the rotating parts due to the unbalanced weight condition.

I wish it understood that my invention is not limited to the specific forms of the invention illustrated and described, or to the arrangement and construction of the parts thereof, as it is capable of numerous modifications and changes without departing from the spirit of the claims.

Having thus described my invention, what I claim as new and desire to secure by Letters Patent, is,—

1. In a rotatable supporting member capable of universal tilting movements around its axis, a shiftable weight counterbalancing

means rotatable with the member, and means automatically operable according to the normal location of the center of inertia of the member relative to its axis of rotation to equalize the weight around such axis.

2. In a rotatable supporting member capable of shifting movements transverse to its axis of rotation, centrifugal operating means automatically operable according to the normal location of the center of inertia relative to the axis of rotation of the member and to the unbalanced shifted transverse position of the member to counterbalance the member.

3. In a rotatable supporting member capable of universal tilting movements about its axis of rotation, automatic means acting according to a tilting of the member and to the normal location of the center of inertia relative to the axis of rotation of the member to counterbalance the member.

4. In a rotatable supporting member capable of shifting movements transverse to its axis of rotation, centrifugal operating means automatically operable according to the extent of shifting movement of the member and to the normal location of the center of inertia relative to the axis of rotation of the member to counterbalance the member.

5. In a rotatable supporting member capable of universal tilting movements about its axis of rotation, means having control valves and operable by an unbalanced weight condition within the member with respect to its axis of rotation to open certain valves and to shift a counterbalancing mass forming a part of the means to a point in the member which is at the opposite side of the axis of rotation of the member to the normal center of inertia thereof, whereby to balance the member with respect to its axis of rotation.

6. In combination, a member mounted for rotary movements and for universal tilting movements with respect to its axis of rotation and having spaces around its axis, and means automatically operable by centrifugal action and by tilting movements of the member and according to the normal location of the center of inertia relative to the axis of rotation of the member to transfer a part thereof into a space in the member located at the opposite side of the axis of rotation to the normal center of inertia whereby to balance the member.

7. In combination, a rotatable supporting member capable of shifting movements transverse to its axis of rotation and having spaces distributed around its axis for receiving a balancing mass, and means including a movable weight equalizing mass operable by centrifugal action upon a rotation of the member and in accordance with the shifting of the member and with the normal location of the center of inertia of the member rela-

tive to its axis of rotation to transfer a portion at least of the mass into a space at the opposite side of the member axis to the center of inertia thereof, whereby the center of 5 inertia is shifted into coincident relation to the axis of rotation.

8. In combination, a rotatable member capable of shifting movements transverse to its axis of rotation and having a series of 10 spaces arranged around its axis for receiving a weight equalizing mass, each of said spaces having an inlet opening, means rotatable with the member and forming a storage chamber for the equalizing mass 15 adapted to have communication with the spaces through the inlet openings, a weight equalizing mass disposed in said chamber, valve means normally closing the openings and operable by a tilting of the member to 20 uncover an opening at a side of the axis of rotation of the member opposed to the normal center of inertia thereof, whereby the mass, by centrifugal action, may enter the communicating space to cause a shifting of 25 the center of inertia into register with the axis of rotation.

9. In combination, a rotatable supporting member tilttable with respect to its axis of rotation and having spaces around the axis, 30 means rotatable with the member and forming a storage chamber for a shifttable weight equalizing mass, said chamber adapted to have communication with said spaces, a shifttable weight equalizing mass contained 35 in the chamber, and means normally closing the communication between the chamber and spaces when the member is in balanced position and automatically operable to open the communication with one or more of the 40 spaces when the member is in unbalanced position with respect to its axis to permit the weight equalizing mass to pass by centrifugal action from the chamber into a communicating space to balance the member.

45 10. In combination, a rotatable supporting member universally tilttable with respect to its axis of rotation and having a storage chamber concentric to its axis for a shifttable weight equalizing mass and also having 50 spaces distributed around its axis with a communicating passage between the spaces and chamber, a shifttable weight equalizing mass in the chamber, and valve means closing the passages between the spaces and chamber when the member is in balanced 55 position and operable according to the normal location of the center of inertia of the member relative to the axis of rotation thereof to uncover certain passages and permit the mass by centrifugal action to enter a space at the opposite side of the axis of rotation to the center of inertia of the member to cause a balancing of the member with respect to its axis.

60 65 11. In combination, a rotatable support-

ing member tilttable with respect to its axis of rotation and having a plurality of spaces arranged around its axis and extending outward therefrom, each space having an inlet opening, means forming a storage chamber 70 in concentric relation to the member axis, and in communication with said openings, a shifttable weight equalizing mass disposed in the chamber and movable therefrom by centrifugal action into the member spaces, 75 and valve means normally closing said openings and operable by an unbalanced tilting of the member to permit a movement of a portion of the mass to a space at the opposite side of the member axis to the normal 80 center of inertia thereof to shift the center of inertia into register with the axis of rotation.

12. In combination, a rotatable member tilttable with respect to its axis of rotation 85 and having a plurality of spaces arranged around its axis and extending outward therefrom, each space having an inlet opening, means forming a storage chamber concentric to the axis of rotation of the member 90 and in communication with each space through its opening, a shifttable weight equalizing mass in the chamber, a compressible means normally holding the member in balanced relation to its axis and closing the 95 openings, said compressible means being operable by an unbalanced condition of the member to permit the centrifugal passage of the mass into a space at the opposite sides of the member axis to its center of inertia to 100 return the member to balanced position when rotated.

13. In combination, a rotatable member tilttable with respect to its axis of rotation 105 and having a plurality of spaces provided in its wall around its axis, means rotatable with the member and forming a storage chamber adapted to have communication with each of the spaces, a weight equalizing mass disposed in the chamber and shifttable 110 by centrifugal action into the spaces of the member, and means closing the communication between the spaces and chamber when the member is in balanced position and operable by an unbalanced tilting of the member 115 to permit a passage of the mass into a space at the opposite side of the axis of rotation of the member to the normal center of inertia thereof to balance the member 120 and shift its center of inertia into register with its axis of rotation.

14. In combination, a shaft having a chamber, a shifttable weight equalizing mass in the chamber, a container carried for rotation with the shaft and for shifting movements relative thereto and having spaces around its axis adapted to have rotation with the chamber, and means normally closing said communication when the container 125 is in balanced position with respect to the 130

- shaft and automatically operable to control an opening of such communication to permit the mass by centrifugal action to enter a space at the side of the axis of rotation of the member opposed to the normal center of inertia to effect a balancing of the member.
15. In combination, rotatable means forming a storage chamber and a tiltable supporting member having weight equalizing pockets arranged around its axis of rotation and in communication with the chamber, a shiftable weight equalizing medium in the chamber adapted to be directed by centrifugal action into the pockets, and means controlling the communication between the pockets and chamber and automatically operable according to the normal location of the center of inertia of the member relative to its axis of rotation to permit the passage of the medium into the pockets at the opposite side of the axis of rotation to the center of inertia to shift the latter into register with the axis of rotation.
16. In combination, rotatable means forming a storage chamber and a supporting member having weight equalizing pockets arranged around its axis of rotation and in communication with the storage chamber, a shiftable weight equalizing medium in the chamber adapted to be directed by centrifugal action into the pockets, and means normally closing the communication between the chamber and pockets and automatically operable by an overbalancing of the supporting member with respect to its axis of rotation to open the chamber communication to a pocket at the lighter side of the axis of rotation to equalize the weight of the rotary means about its axis.
- 40 17. In combination, rotatable means forming a storage chamber and a tiltable supporting member having weight equalizing pockets arranged around its axis of rotation and in communication with the chamber, a shiftable weight equalizing medium in the chamber adapted to be directed by centrifugal action into the pockets, and means normally maintaining the supporting member in balanced position with respect to its axis of rotation and normally closing the communication between the chamber and pockets, said latter means being automatically operable by an overbalancing of the supporting member to open the chamber communication to a pocket at the lighter side of the axis of rotation to equalize the weight of the supporting member about its axis.
- 60 18. In combination, a member mounted for rotary movements and for universal tilting movements with respect to its axis of rotation, and means acting according to the tilting movements of the member and to the normal location of the center of inertia of

the member relative to the axis of rotation thereof to counterbalance the member.

19. In combination, a member mounted for rotary movements and for universal tilting movements with respect to its axis of rotation and about different centers which are spaced longitudinally of the axis of rotation, a shiftable counterbalancing mass carried by the member and shiftable upon a rotation of the member, and means operable by a tilting of the member about one of its tilting centers to control the shifting of the mass to counterbalance any unevenness in the weight of the member about its axis of rotation.

20. In combination, a member mounted for rotary movements and for universal tilting movements with respect to its axis of rotation and about different centers which are spaced longitudinally of its axis of rotation, said member having a center chamber and pockets radiating therefrom in equidistantly spaced relation around the member axis, a shiftable mass normally stored in the center chamber and adapted to pass into the pockets upon a rotation of the member, and means operable by a tilting of the member about one of its tilting centers to control the admission of the shiftable mass into the pockets whereby the weight of the member is equalized with respect to its axis of rotation.

21. In combination, a rotatable supporting member capable of shifting movements transverse to its axis of rotation about different centers which are spaced longitudinally of the axis of rotation, said member having a central chamber with radiating pockets, a shiftable weight counterbalancing mass disposed in the central chamber and shiftable into the pockets by centrifugal action, valve means operable by a predetermined transverse shifting of the member to control the distribution of the mass to the pockets in accordance with the unbalanced condition of the member whereby it is balanced with respect to its axis of rotation, and means for rotating the member.

22. In combination, a rotatable supporting member, capable of universal tilting movements with respect to its axis of rotation, and with its tilting centers spaced longitudinally of the axis of rotation, said supporting member having a part forming a centrally disposed chamber with pockets radiating therefrom and in substantially the plane of one of the tilting centers of the member, a shiftable mass disposed in said chamber and movable therefrom into the pockets by centrifugal action, and means controlling the communication between the chamber and pockets and operable in accordance with a tilting of the member to admit a portion of the mass to the pockets

to equalize the weight of the member around its axis.

23. In combination, a shaft mounted for rotary and limited universal transverse 5 tilting movements, a supporting member carried by the shaft for rotary and tilting movements therewith, and means automatically operable by a tilting of the shaft and

by centrifugal action to transfer the normal center of inertia of the member into 10 register with its axis of rotation, whereby a balancing rotation of the member is effected under varying load conditions.

In testimony whereof, I have hereunto signed my name to this specification.

WILLIAM EMIL BOCK.
